REFRIGERATION

Gunnar Grubb, Stockholm, Sweden, assignor, by
mesne assignments, to Servel, Inc., New York,
N. Y., a corporation of Delaware

Application August 12, 1936, Serial No. 95,492
In Germany August 27, 1935

17 Claims. (Cl. 62—118)

This invention relates to refrigeration apparatus or systems of the non-continuous or intermittent or periodic type.

The purpose of the invention is to improve the operation of systems of this type, and this is accomplished by the modification of a more or less standard intermittent system by the addition of a preferably separately hermetically sealed intermittent system, one or more parts of which are in heat exchange relation with the first-mentioned system. More specifically, the added system includes a generator-absorber in heat exchange relation with an absorption liquid circulation circuit of the first system, or otherwise arranged so that such generator-absorber may be heated only by heat from an internal place of heating, that is, by heat of absorption transferred from the first system. By this arrangement, the production of refrigeration is rendered more continuous than by means of one intermittent system alone, inasmuch as the components of the compound system operate alternately. Furthermore, the component parts of such a compound system can operate at different temperatures or temperature ranges and thus the heat receiving portions of the respective components can be utilized to absorb heat from different temperature compartments of a refrigerator cabinet or groups of refrigerator cabinets, or other objects to be refrigerated.

In a preferred form of the invention I have applied the same to the character of system described in an application Serial No. 718,136 filed by Carl Georg Munters on March 30, 1934, Patent No. 2,086,632 but it will be understood that the invention is not limited to the specific apparatus therein described. However, for purposes of description, it may be considered that the disclosure of said Munters application Serial No. 718,136 is incorporated in this application.

The present invention will be described in conjunction with the accompanying drawing showing a preferred form thereof more or less diagrammatically, which drawing forms a part of this specification.

Fig. 1 is a diagrammatic elevation view partly in cross section showing one embodiment of the invention; and

Fig. 2 is a similar view of an alternative part for some of the structure shown in Fig. 1.

The system shown in Fig. 1 includes an absorption liquid reservoir 10 of sufficient volume to hold the bulk of absorption liquid in the system. This reservoir is preferably exposed to the cooling influence of surrounding air. To one side of the

reservoir 10 is a vessel 14 which may be termed a generator or separator or be considered as a part of a vapor expeller. This vessel is not directly heated, though it may be. In the embodiment illustrated, the contents of vessel 11 are heated by a conduit 38, 39, 40 including a vapor lift coil 39 which is in heat exchange relation with a flue 41 which may be suitably heated as by a gas burner or by an electric heater disposed therein.

Between vessels 10 and 14 is a liquid heat exchanger 12 including inner and outer pipes forming heat exchange spaces for flow of liquid. The inner pipe of the heat exchanger is connected by a conduit 13 to the lower part of vessel 14, and is connected at its other end by a conduit 11 to the reservoir 10. These parts form a conduit for flow of liquid from the bottom part of vessel 14 to reservoir 10.

Connected to the top of reservoir 10 is a vertical conduit 21, the upper end of which is connected to a vessel 19 which is normally filled or substantially filled with liquid. A conduit 15, 16, 18 is connected to the lower part of reservoir 10 and extends upwardly to connect with vessel 19. This conduit includes a horizontal loop 16 constituting an absorption liquid cooling element having fins 63 for increasing the heat transfer surface. Also connected to vessel 19 is a strong liquor conduit 33. Parts 15, 16, 18, 19, 21 and 33 constitute an absorption liquid containing structure extending above reservoir 10. This structure is connected to the liquid space of the absorption liquid containing part of the system so that, practically at all times, this structure is filled or substantially filled with liquid due to the fact that, these parts being exposed to atmosphere, the temperature of the fluid therein is such that for the pressure prevailing in the system and in view of the concentration of solution, all the gas can be dissolved and remain in solution form.

The bottom of pipe 33 is connected to the outer pipe of the liquid heat exchanger 12. A conduit 32 extends between the other end of the outer conduit of the heat exchanger and the lower part of an annular chamber 31 within vessel 9 formed between vertically disposed cylinders. Chamber 31 is closed at the bottom except for conduit connections and is open at the top. The upper edge of the inner cylinder provides an overflow edge. The central space 34 is connected at the bottom with a tube 24. This tube contains a liquid reaction head for gas lift structure.

A conduit 28 is connected to the bottom of tube 24 and is connected to a gas lift coil 29 surrounding flue 41. The upper end of coil 29 is connected

by means of conduit 30 to the space 31. A second conduit 25 is connected to the lower end of tube 24 and is connected to a gas lift coil 26, the upper end of which is connected by a pipe 27 with the 5 upper part of vessel 14. A vapor conduit 36 connects the upper part of vessel 14 with the space 34.

A volume variation vessel 22 is connected by means of conduits 23 and 37 with the tube 24 and 10 the vessel 9.

A conduit 44 extends upwardly within a rectifier jacket 46 to which is connected a condenser loop 45 having fins 17 thereon exposed to atmospheric air for cooling. The rectifier 46 is connected by means of a conduit 48 with an evaporator 49 situated within a space to be cooled denoted by the line 80.

Connected to the evaporator 49 is a conduit 50 adapted to receive residue absorption liquid 20 from the bottom of the evaporator. A conduit 51 is connected to the tube 50 and is connected to a jacket 68. Connected to jacket 68 is an overflow tube 51 which has a part 52 in heat exchange relation with the volume variation vessel 25 22 and which is connected to pipe 15 at 43. A pipe 42 is connected above point 43 to conduit 15 and is connected at a higher elevation to the conduit 37.

The operation of the part of the system so far 30 described is set forth at length in the aforementioned application of Munters and will be here briefly described, reference being had to the aforesaid application for a more detailed description of operation if desired.

35 During a high pressure period heat is applied in the flue 41. This causes generation of vapor in the three gas lift coils 26, 29 and 39. These are places of external heating. Coil 39 is merely a local circulator for the generator vessel 14. 40 Coil 26 causes a lifting of liquid and vapor from the bottom of tube 24 to the upper part of vessel 14. In vessel 14 the vapor generated is separated from the liquid. The liquid flows downwardly within vessel 14, through conduit 13, through the 45 inner conduit of the heat exchanger 12, and through conduit 11 to the reservoir 10. From reservoir 10 liquid circulates upwardly through conduit 21, through vessel 19, through conduit 33, through the outer space of heat exchanger 50 12, through conduit 32 and into space 31. Liquid in space 31 is pushed upwardly therein due to the lifting of liquid and vapor by coil 29 and the liquid overflows into space 34 and down into tube 24 whence the liquid is returned to the 55 vessel 14 by means of coil 26.

The expelled vapor passes through conduit 36 and flows upwardly through the overflow liquid in vessel 9. The vapor thence flows upwardly through conduit 44 and is condensed in condenser loop 45. Entrained water vapor is removed from the refrigerant vapor in the analyzer space 34 and the rectifier 46 and returns to the lower part of the system. Liquid refrigerant is forced through conduit 48 into the evaporator 49 65 where it collects. During this period there is little or no circulation through conduit 15, 16, 18. The expulsion of refrigerant vapor continues until the evaporator contains so much liquid refrigerant that there is overflow through conduits 70 50, 51 and 51'. Liquid overflow through conduits 51 and 51' consists at first of absorption liquid. This liquid flows in heat exchange relation with the volume variation vessel 22 at 52 but the absorption liquid is not vaporized. When, 75 however, substantially pure refrigerant overflows

through conduit 51, it becomes vaporized at point 52. The introduction of vapor from conduit 51' into conduit 15 causes a circulation to set up, which circulation of warm liquid may be utilized by means of a thermostat or through other 5 means to shut off the heat to the generator, thereby closing the generating period.

When heat is shut off, the liquid in space 31 drops since the coil 29 is no longer effective, and as this liquid drops a corresponding column 10 of liquid in conduit 42 recedes until conduit 42 is devoid of liquid, whereupon gas has free entry into conduit 15 from the evaporator through conduits 48, 44, 37 and 42. Now an absorption period starts, which period is at reduced pressure. During this period a circulation is set up from reservoir 10 through conduit 15, loop 16, conduit 18, vessel 19, and downwardly through conduit 21. The heat of absorption produced in the places of internal heating, conduits 15 and 20 16, is rejected from the absorber cooling coil 16.

So far the system described is one of a number of systems to which the invention may be applied. The system so far described may be called the primary system. It may contain ammonia and 25 water or other refrigerant and absorption liquid and preferably is made of steel vessels and tubes welded together and hermetically sealed.

In accordance with my invention I place the absorber cooling coil 16 in heat exchange relation 30 with a generator-absorber 61 of a separate hermetically sealed intermittent system. The generator-absorber 61 may contain a solid absorbing agent 62, for example, calcium chloride suitably treated as known in the art, or any of various known solid absorbents, particularly those including an element of the halogen group. A plurality of fins 69 extend into and from the generator-absorber 61 so that there is good heat transfer relation between the cooling loop 16 40 and the generator-absorber and also heat transfer with respect to atmosphere.

Connected to the generator-absorber is a conduit 64 which is connected to a condenser 65, in turn connected to an evaporator 67 including a 45 loop connected to a receiver 66. Conduit 64, on which the condenser fins 65 are arranged, passes through the previously described jacket 68 so as to be in heat exchange relation with overflow liquid from the evaporator 49 of the primary system. As the refrigerant the secondary system may, for example, utilize methylamine.

Let us first consider the operation of the secondary system during the expulsion period of the primary system. Evaporator 67 contains the 55 secondary refrigerant. Since there is little or no circulation through loop 16 during this period the generator-absorber 61 can readily dissipate heat to the atmosphere, and thus the refrigerant is absorbed therein and flows from evaporator 60 67 through conduit 64 and into the generator-absorber. The refrigerant within evaporator 67 is thus vaporized and withdraws heat from the surroundings, producing refrigeration. The refrigeration supplied by evaporator 67 during this 65 high pressure period of the primary system at least in part bridges the hiatus of evaporation in the primary system. Inasmuch as the primary system and the secondary system can be so constructed that the two evaporators operate at 70 different temperatures, the primary system may, for example, be utilized for production of ice or other low temperature use, while the secondary system can, for example, be used for high temperature cooling, such as that of a food space. 75

During the absorption period of the primary system there is an intense circulation through conduits 15, 16 and 18 wherefore considerable heat is given off to the generator-absorber 61. 5 This causes expulsion of methylamine from the absorbent and the vapor is condensed in condenser 65 and accumulates in evaporator 67. If desired, the condenser may be placed behind the evaporator as is generally known in the art by 10 the term "dead end condenser", or the evaporator may have a receiver outside the refrigerated space so as to avoid undue heating of the refrigerated space during the expulsion period of the secondary system. 15 It may be advantageous under certain circumstances to utilize an indirect system for the withdrawal of heat from the generator-absorber 61. Fig. 2 shows a system for accomplishing this in which the generator-absorber 61 is surrounded by 20 a cooling coil 71. This coil is connected to a dome 77 on a vessel 72 which is in turn connected by means of a conduit 73 with an additional coil 74 surrounding the flue 41. The upper end of coil 74 is connected by means of a conduit 73 to 25 a condenser 75 having fins 76 and which drains into the bottom of coil 71. A pipe 78 connects dome 77 with the upper part of the condenser. Let us assume that liquid is contained in this 30 separate indirect cooling system to the height indicated at 79. The vessel 72 and coil 74 are therefore filled with liquid. During the heating period of the primary system vapor is driven off in coil 74 and liquid and vapor are carried upwardly in conduit 73 to the condenser 75. The 35 liquefied fluid flows to the coil 71 where it is partially vaporized and absorbs heat from the generator-absorber 61. The coil 71 acts as a gas lift device and the liquid and vapor are lifted up to the dome 77 whence the vapor passes through 40 conduit 78 to be re-condensed and the liquid passes through vessel 72 to be re-circulated by the gas lift coil 74.

When the heating of the flue 41 is discontinued, that is, during the absorption period of the primary system, the vapor lift effect of coil 74 is discontinued. Thus no more liquid is supplied 45 through conduit 73 to condenser 75, and coil 71 is quickly depleted of its liquid content, wherefore this system becomes ineffective to transfer heat 50 from the generator-absorber.

It will be obvious to those skilled in the art that the invention is not limited to the specific apparatus disclosed.

What is claimed is:

55 1. Refrigeration apparatus including a system having alternate periods of expulsion of refrigerant from absorbent and evaporation of refrigerant and including vessels and conduits forming at least two circuits for circulation of absorption liquid so constructed and arranged that during 60 periods of refrigerant expulsion absorption liquid circulates in one of said circuits without producing circulation in the other of said circuits, an evaporator, an absorber, a conduit connecting said evaporator and said absorber, and said absorber being in heat exchange relation with a part of the other of said circuits.

2. Refrigeration apparatus including a system having alternate periods of expulsion of refrigerant from absorbent and evaporation of refrigerant and including vessels and conduits forming at least two circuits for circulation of absorption liquid so constructed and arranged that during 70 periods of refrigerant expulsion absorption liquid circulates in one of said circuits without pro-

ducing circulation in the other of said circuits, an evaporator, an absorber, a conduit connecting said evaporator and absorber, said evaporator and absorber constituting a secondary system 5 separate from the system including said circulation circuits, and said absorber being in heat exchange relation with a part of the other of said circuits.

3. Refrigeration apparatus including a system having alternate periods of expulsion of refrigerant from absorbent and evaporation of refrigerant and including vessels and conduits forming at least two circuits for circulation of absorption liquid so constructed and arranged that during 10 periods of refrigerant expulsion absorption liquid circulates in one of said circuits without producing circulation in the other of said circuits, an evaporator, an absorber, a solid absorbent in said absorber, a conduit connecting said evaporator and said absorber, and said absorber being in heat exchange relation with a part of the other of said circuits.

4. Refrigeration apparatus including a system having alternate periods of expulsion of refrigerant from absorbent and evaporation of refrigerant and including vessels and conduits forming at least two circuits for circulation of absorption liquid so constructed and arranged that during 15 periods of refrigerant expulsion absorption liquid circulates in one of said circuits without producing circulation in the other of said circuits, an evaporator, an absorber, a solid absorbent in said absorber, a conduit connecting said evaporator and said absorber, and said absorber being in heat exchange relation with a part of the other of said circuits.

5. Refrigerating apparatus including at least two separately hermetically sealed intermittent absorption systems, one of said systems having at least two alternately heated circuits for circulation of absorption liquid and the other of said 25 systems having a generator-absorber in heat exchange relation with one of said circuits.

6. Refrigerating apparatus as set forth in claim 5 in which hot fluid flowing in one system is cooled by cold fluid flowing in another of the 45 systems.

7. In absorption refrigeration apparatus of the kind having alternate periods of absorption at low pressure and expulsion of refrigerant from solution at higher pressure, a generator, a first evaporator, a storage reservoir of sufficient volume to hold the bulk of absorption liquid in the system, members forming a circuit for circulation of liquid through said reservoir including an upwardly extending conduit, means to conduct vapor from said evaporator to said circuit, a second evaporator, a generator-absorber in heat exchange relation with said circuit, and a conduit connecting said second evaporator with said 50 generator-absorber.

8. In a refrigeration system of the kind having low pressure periods of refrigerant evaporation and absorption alternating with higher pressure periods of vapor expulsion and including a main circuit and an auxiliary circuit for circulation of absorption liquid in the latter of which there is substantially no circulation of absorption liquid during the higher pressure periods of vapor 70 expulsion, the improvement which consists in utilizing the heat of absorption in said auxiliary circuit during the lower pressure periods of refrigerant evaporation to expel refrigerant from an absorbent.

9. In a refrigeration system of the kind having low pressure periods of refrigerant evaporation and absorption alternating with higher pressure periods of vapor expulsion and including a main circuit and an auxiliary circuit for circulation of absorption liquid in the latter of which there is substantially no circulation of absorption liquid during the higher pressure periods of vapor expulsion, the improvement which consists in utilizing the heat of absorption in said auxiliary circuit during the lower pressure periods of refrigerant evaporation to expel refrigerant from an absorbent and utilizing the refrigerant so expelled to produce evaporation when such heat of absorption is not produced.
10. In refrigeration apparatus including a system having alternate periods of expulsion of refrigerant from absorbent and evaporation of refrigerant and including vessels and conduits forming a circulation circuit for absorption liquid, an evaporator, an absorber, a conduit connecting said evaporator and said absorber, and said absorber being in heat exchange relation with a part of said circuit.
11. Refrigeration apparatus including a first evaporator, a generator-absorber, a vapor conduit connecting said generator-absorber with said evaporator, a second evaporator, means for supplying liquid to said second evaporator, a liquid overflow conduit connected to said second evaporator, said liquid overflow conduit and said vapor conduit being in heat exchange relation.
12. Refrigeration apparatus including a first circuit for circulation of absorption liquid, a second circuit for circulation of absorption liquid, heating means to cause circulation in one of said circuits without producing circulation in the other of said circuits, and a heat transfer system connected between said other of said circuits and a space to be cooled.
13. In refrigeration apparatus having alternate periods of absorption and vapor expulsion, an expeller, an absorber including a cooling element and connected with said expeller, a generator-absorber in heat exchange relation with said absorber cooling element, and cooling means for said generator-absorber active upon application of heat to said expeller.
14. Apparatus as set forth in claim 13 in which the cooling system for the generator-absorber is a fluid containing system and in which there is a common heating means for fluid in said system and for the expeller.
15. In refrigeration apparatus including a system having alternate periods of expulsion of refrigerant from absorbent and evaporation of refrigerant and including vessels and conduits forming a circulation circuit for absorption liquid, an evaporator, an absorber, a conduit connecting said evaporator and said absorber, said evaporator and absorber constituting a secondary system separate from the system including the circulation circuit, and said absorber being in heat exchange relation with a part of said circuit.
16. A method of refrigeration which includes flowing absorption liquid alternately in different paths having separate places of external and internal heating respectively to carry out an intermittent absorption refrigeration cycle, and utilizing heat from the place of internal heating to supply input for an alternate intermittent refrigeration process.
17. Refrigeration apparatus including a first intermittent absorption refrigeration system having places of external and internal heating separated and in alternate paths of absorption liquid flow, and a second intermittent refrigeration system operated by heat input from said place of internal heating.

GUNNAR GRUBB.
